UNITED STATES PATENT OFFICE.

ALFRED JOHN SHEA, OF HOLYOKE, MASSACHUSETTS.

PUZZLE.

Application filed April 17, 1924. Serial No. 707,164.

To all whom it may concern:

Be it known that I, ALFRED J. SHEA, a citizen of the United States, residing at Holyoke, in the county of Hampden and 5 State of Massachusetts, have invented new and useful Improvements in Puzzles, of which the following is a specification.

This invention relates to puzzles.

The object is to provide a puzzle of the 10 class in which its solution consists in the separation of certain parts comprising the puzzle, said parts seemingly being inseparable, but by certain movements and manipulations of the several elements, may be 15 readily separated.

Another object is to provide a device of this class for affording entertainment and amusement to those attempting to solve the puzzle, said device being small and handy 20 and capable of being arranged into a compact form so as to be readily carried in the pocket and easily and quickly placed in condition for use again.

A full and complete understanding of the 25 invention may be obtained from a consideration of the following detailed description, taken in connection with the accompanying drawing forming a part of this specification, it being understood that while the drawing 30 shows a practical form of the invention, the latter is not to be confined to strict conformity with the showing thereof, but may be changed or modified, so long as such changes or modifications mark no material 35 departure from the salient features of the invention, as specifically pointed out in the appended claims.

In the drawing, in which similar reference characters designate corresponding parts 40 throughout the several figures:—

Figure 1 is a perspective view of the improved puzzle and showing the initial step in solving the same;

Figure 2 is a similar view of a portion 45 thereof and showing the second step in the solution;

Figure 3 is a perspective view of the entire device and showing a subsequent step;

Figure 4 is a view similar to Figure 2, 50 and showing a further step in the solution; and

Figure 5 is a detail longitudinal section through one of the elements or "pieces".

The improved puzzle comprises a pair of 55 separate members which will hereinafter be termed "pieces", which are of elongated

form and preferably of a size and shape to about fill the hand when closed. These pieces are formed exactly alike, and are provided with three holes through which 60 are passed in a certain manner, a cord or other flexible member, the said cord being endless and doubled before threading the same through said holes. Each end of the doubled cord is made fast to a piece in a 65 manner which, at first sight, appears to be impossible of release, and threaded on the intermediate portion of the strands of the doubled cord are one or more balls or beads, the object sought, in the solution of the puzzle, being to remove said balls from the 70 cords.

Since the members or pieces are identical in form and construction, a description of 75 one will suffice for both and the same reference characters are therefore assigned to each.

The pieces 1 are preferably formed of wood, celluloid or any other durable material which is light, strong and non-corrosive, and they are preferably formed with rounded ends and are somewhat wider than thick with their opposite faces slightly tapered towards the ends and convex transversely of the piece. 80

Each piece is provided adjacent to one end with a transverse bore or hole 2, and equidistant from the other end there is provided another transverse bore or hole 3, while midway between these holes, each 90 piece is provided with a central bore or hole 4. For the purpose of rendering this description more easily understood, the hole 2 will hereinafter be referred to as the "inner" hole, the hole 3 as the "outer" hole, and the 95 hole 4 as the "middle" hole.

An endless cord 5, or other suitable flexible member, is doubled on itself to provide parallel strands, the ends of the strands, where joined together, being designated at 100 6, and these strands are secured to the pieces 1 by first passing the ends 6 upwardly through the inner hole 2, then extending the strands longitudinally of the piece and passing said end downwardly through the outer hole 3 in an opposite direction, then passing the end portion of the strands backwardly to the middle hole 4 and up and through the same, where the closed end 6 incloses that portion of the strands which extends from the inner to the outer holes. This is shown 105 at the right hand side of Fig. 1.

Prior to threading the strands through the several holes in the manner above described, a pair of balls or beads 7, preferably formed of wood, glass or other suitable material, and having bores or passageways, are threaded on the said strands and are normally located at an intermediate point of the same. The object of the puzzle is to solve the problem of taking the said balls or beads off of the strands, of course, without breaking the cord, and again to put the said balls or beads back again on the cord in their normal positions.

Assuming that the puzzle is assembled as above described and with the cords drawn taut, as illustrated at the right hand side of Figure 1 of the drawing, and it is desired to remove the balls, the initial step is to loosen the strands through the several holes 2, 3 and 4, and by grasping the end 6 to elevate the same, as indicated at the left hand side of Figure 1. The end 6 is then directed downwardly, as indicated in Figure 2 of the drawing, and passed through the inner hole 2, in a direction opposite to the direction of the first passage of the strands when assembling the parts. Sufficient slack is given the strands by drawing the same through the holes in an obvious manner. The end 6 is then drawn downwardly below the piece 1 to form a loop 8, care being taken that the right hand strand where coming up through the middle hole 4 shall be on the right of the other parts of the strands when the said end 6 is passed downwardly through the inner hole 2, as clearly shown in Figures 2 and 3.

With the loop 8 drawn through until sufficiently large, the remainder of the cord, together with the other piece 1 and the aforesaid balls 7, may then be freely passed through said loop, as will be clear from an inspection of Figure 3, after which the end 6 forming part of the loop 8 may be released from the holes 2, 3 and 4, as shown in Figure 4, and the balls may then, if desired, be removed from the cord, and part of the puzzle is then solved.

A reversal of the above operations will serve to apply the cord and the balls in their normal relation to the piece 1, as will be apparent, and it is therefore not deemed necessary to recite the several steps to be taken to secure such result.

When not in use, the strands may be wrapped about the two pieces and the device readily carried in the pocket or put away in a small space. Instead of the balls or beads 7, I may use cards or other elements threaded on the strands.

From the foregoing it will be seen that a simple, strong and durable device of this character has been provided, which will serve to amuse and entertain and exercise the ingenuity of persons endeavoring to

solve the puzzle, the parts being of such simple construction as to be capable of manufacture at a low cost, and therefore admirably adapted for advertising purposes, the surfaces of the pieces 1 offering suitable spaces for such advertisements, if desired.

What is claimed is:—

1. A puzzle comprising two separate pieces, each having three spaced holes therein, an endless cord formed into two strands threaded through said holes, and one or more elements mounted on said strands between said pieces.

2. A puzzle comprising two separate pieces, each having three spaced holes therein, an endless cord formed with two strands joined at each end, and one or more balls or beads mounted on the strands between said pieces.

3. A puzzle comprising a pair of separate pieces each having an inner hole near one end, a middle hole and an outer hole near the other end, an endless cord drawn to form two parallel strands joined together at each end, one or more balls or beads having bores and threaded on said strands to an intermediate point thereof, each end of the connected strands being first passed through the inner hole of one of the pieces, then through the outer hole in an opposite direction, then through the middle hole in a direction corresponding to the first passage, the joined ends of the strands being looped around that portion of the same extending from the inner to the outer holes.

4. A puzzle comprising a pair of separate pieces each having an inner hole near one end, a middle hole and an outer hole near the other end, an endless cord drawn to form two parallel strands joined together at each end, one or more balls or beads having bores and threaded on said strands to an intermediate point thereof, each end of the connected strands being first passed through the inner hole of one of the pieces, then through the outer hole in an opposite direction, then through the middle hole in a direction corresponding to the first passage, the joined ends of the strands being looped around that portion of the same extending from the inner to the outer holes, said parallel strands being of sufficient length to allow slack to be drawn through the holes and permit one of the said joined ends to be passed through the inner hole of its respective piece in a direction opposite to the first passage and to form a loop of a size to permit the remainder of the strands, the balls and the other piece to be passed therethrough for freeing the first piece and removing the balls from the strands.

In testimony, that I claim the foregoing as my own, I have hereto affixed my signature.

ALFRED JOHN SHEA. 130
